UNITED STATES PATENT OFFICE.

FRANK C. ANDERSON, OF CINCINNATI, OHIO, ASSIGNOR TO THE AMERICAN VALVE & METER COMPANY, OF CINCINNATI, OHIO, A CORPORATION OF OHIO.

FOOT-LEVER.

1,086,575.

Specification of Letters Patent.

Patented Feb. 10, 1914.

Application filed April 29, 1910. Serial No. 558,493.

To all whom it may concern:

Be it known that I, FRANK C. ANDERSON,
a citizen of the United States, residing at
Cincinnati, in the county of Hamilton and
5 State of Ohio, have invented certain new
and useful Improvements in Foot-Levers, of
which the following is a specification.

My invention relates to safety devices for switches.

10 The object of my invention is to provide simple and efficient means for automatically closing the elongated slot in which the foot treadle travels when the foot treadle is in its uppermost position, and thus protect the 15 operating means of the switch safety mechanism from the weather.

My invention consists in providing means for automatically closing the elongated slot in the housing which contains the means for operating the interlocking mechanism.

My invention also consists in certain parts and combination of parts as will hereinafter be set forth and claimed.

In the drawings, which serve to illustrate
25 the preferred construction and operation of
my invention Figure 1 is a front elevation
of a switch stand, the housing containing
the interlocking mechanism and the target
operating mechanism being shown in sec-

30 tion. Fig. 2 is a plan view of the switch stand shown in Fig. 1. Fig. 3 is a perspective view of the handle plungers employed on the switch stand equipped with my invention. Fig. 4 is a perspective view of the 35 connecting link to engage the interlocking

mechanism with the handle plungers of the switch stand. Fig. 5 is a plan view of the switch stand, point rail, and my improved safety device. Fig. 6 is an enlarged end ele-

40 vation illustrating my improved automatic shutters closing the slot in the front of the housing containing the operating means for the interlocking mechanism. Fig. 7 is a sec-

45 tional view taken on the line 7—7 of Fig. 6. Fig. 8 is a perspective view of one of my improved shutters. Fig. 9 is a plan view of my improved target mechanism applied to a switch stand of a different design. Fig. 10 is a perspective view of cover plate for

50 the automatic shutters.

In the embodiment of my invention, as set forth, I show a switch stand 1 of a well known type having a suitably mounted operating shaft 2 which is connected at its

bottom to an operating rod 3, connected to head rod 3' which in turn is connected to point rails 4. The switch stand 1 is provided with a top plate 5 upon which is mounted a fulcrum head 6. This fulcrum head is provided with an operating handle 7 pivoted thereto and is pinned and keyed to the operating shaft 2. The operating handle 7 engages slots 8 in the plate 5 of the switch stand in the usual manner. The switch stand shown is of the 90° type, the handle 7 being adapted to throw 90° from one slot 8 to the other slot 8. 55 60 65

Placed adjacent the switch stand 1 is a housing 9 mounted upon a plate 10 on the head blocks or ties 11. Mounted in said housing 9 I provide a foot treadle 12 having an operating gear rack 13, in which is mounted a shaft 14, having an eye 15 at the end thereof, to which is attached a chain 16 having a pad lock 17 thereon. The foot treadle 12 operates in an elongated slot 12' which is placed in the end plate 9' bolted to the end of the housing 9. The operating gear rack 13 is adapted to engage a segmental gear 18 pivotally mounted inside the housing 9 and having a bell crank 19 thereon which engages a suitable lifting member 20 mounted on a shaft 21 in the housing 9. A link 22 is pivotally secured to the top of the shaft 21, outside the housing 9, and is provided with a bifurcated portion 23 at the end adapted to engage the lower end of the hub 24 of the sliding handle plungers 25, thereby operating said sliding plungers when the shaft 21 is operated. 90

The sliding handle plungers 25 are provided with spline ways or grooves 26 which are adapted to receive splines 27 on the inside of the switch stand 1, as best shown in Fig. 2. In the mechanism here shown the 95 plunger 25 is adapted to engage recesses or openings 28 in the handle 7 when the switch is in its closed position and when the plungers are in their lowermost position. These handle plungers are provided for the purpose of engaging the handle in their uppermost position to prevent the locking of the switch stand, and to engage the recesses in the handle of the switch stand in their lowermost position only when the switch 100 is properly closed and thus permit the locking of the switch stand. These handle plungers are made plural to engage the handle 105

of the switch stand in either a right or left position and also to protect the switch from being locked when set for the siding which frequently occurs, causing a disastrous wreck. The slots 8 in the plate 5 are sufficient means for holding the switch when set for the siding without the additional use of the pad lock. The handle is provided with a recess that will only engage one of the 10 plungers when in the lowermost position, that is, when the switch is properly closed to engage a pad lock.

A boss or eyelet 29 is preferably provided at the top of the handle 7 which is adapted 15 to be engaged by the pad lock for the switch stand. Thus, if the operator attempts to lock the switch stand with the pad lock 17, the plungers must be in their lowermost position and enter the recess 28 at the lower 20 end of the handle 7. In closing the switch if the switch is not properly closed the handle plungers 25 will be in their highest position and the eyelet 29 will remain in the walls of the fulcrum for the handle 7 sufficiently to prevent the operator from placing the handle 7 into position to engage the eyelet 29 with the pad lock, thus clearly indicating to the operator that the switch has not been properly thrown or closed. The 30 segmental gear 18 is also adapted to engage a gear rack 30 which is mounted upon a plunger rod 31 in the plunger housing 32. The plunger 31 is adapted to engage an opening or openings in the end of the interlocking bar 33, and is spring pressed by means of the spring 34 bearing against a projection 35 in the plunger housing 32 and against a collar 36 pinned to the plunger 31 near the other end of the housing 32.

When it is desired to open the switch, remove the pad lock 17, from the handle 7, raise the handle to horizontal position, and push the foot treadle 12 downwardly to its lowermost position, thereby operating the 45 segmental gear 18, which in turn operates the gear rack 30, which, being fastened to the plunger 31 moves said plunger out of engagement with the interlocking bar 33 against the pressure of the spring 34. At 50 the same time the shaft 21 in the housing 9 is raised thereby raising the handle plungers 25 and lowering the shaft 14 to its lowermost position, as shown by dotted lines.

Placed at one end of the plate 10 is a 55 stand 38 through which extends a target shaft 39 upon which is mounted a target 40 having the customary flag signals thereon. A smaller housing 41 is placed below the plate 10 in alinement with the plunger housing 32 and has mounted therein and upon the end of the shaft 39 a target arm 42. The target arm 42 is connected to the interlocking plunger by means of a link 43 and coupling 37. Thus, when the plunger 31 is operated, the target shaft 39 which is con-

nected thereto is rotated simultaneously therewith, thereby insuring that the target is always in proper position relative to the switch, and preventing an operator from showing a clear signal when the switch is 70 open.

When the foot treadle 12 is in its uppermost position, the lower part of the elongated slot is open to the weather. To protect the inside operating means and switch 75 interlocking mechanism from the weather, I provide shutters 44 which have beveled edges 45 at the top to allow the beveled edge 46 of the treadle 12 to force them apart. The shutters 44 are pivoted at 47 in an inclosure 48 on the outside of the housing 9 and are spring pressed by means of springs 49. The shutters 44 are provided with sockets or recesses 50 in the side thereof in which fit the springs 49. A plate 51 is 85 mounted on the inclosure 48 to close the same and is provided with a hole to allow the socket 50 on the shutter 44 to pass therethrough. Thus, it is seen, that when the treadle 12 is moved downwardly it spreads 90 the shutters 44 against the pressure of the springs 49, and immediately upon the return of the foot treadle 12 to its uppermost position the shutters are closed automatically by means of the springs 49. In this manner, the 95 slot 12' is always closed to protect said mechanism against the weather except when the switch is being operated.

If it is desired to equip a switch stand of the 180° type with my improved target apparatus, it is necessary to place the target stand 38 in a position where it will not interfere with the movement of the handle 7 of the switch stand. To accomplish this I provide a bell crank lever 52 in the housing, 53, the same being mounted upon pivot 54 and having one arm connected to the connecting link 43 and the other arm to a connecting rod 55 which is connected to the target arm 42 in the housing 41 directly beneath the target stand 38 all arranged as shown in Fig. 9. With this arrangement, the handle 7 is swung farther around than in the preceding figures, and therefore necessitates moving the target stand 38 and target shaft 39 out of contact therewith. This arrangement is necessary unless I use another head block and a longer plate in order to throw the target shaft out of the way of the operating handle of the switch stand 100 for stands that operate 180°. In that case I can dispense with the housing 41 and the bell crank lever 52. The 180° switch stand requires a slight change in the plunger mechanism but it may be worked on the same 110 principle as shown in Fig. 9.

In Fig. 1 I show a switch stand and safety mechanism in combination therewith, said switch stand having handle plungers engaging the safety mechanism in such a manner 120

as to prevent the locking of the switch stand unless the switch is properly closed. For stands now in service, that have no provision to engage handle plungers, the shaft 5 14 may be provided with an eye to engage a flexible connection attached to the pad lock, thus preventing the use of the pad lock when the switch is in open position and the shaft 14 of the foot treadle 12 is in its lowermost position, but when the switch is properly closed the shaft 14 will travel to its uppermost position and permit the use of the pad lock for locking the switch stand.

It will be seen that I provide means 15 adapted to engage handle plungers for a specially designed switch stand to control the locking of said switch stand, and means adapted to engage a flexible connection for controlling the use of a padlock for locking 20 switch stands of the ordinary type not specially designed for handle plungers except when the switch is properly closed. Said means is adapted to engage target mechanism whereby it is impossible for the operator 25 to operate the target independently of the switch stand and thereby show a clear signal on the target when the point rail of the switch is not properly closed. In other words, the present construction of switch 30 stand permits the operator to throw the switch and show a clear signal even if there should be an obstruction between the point rail and stock rail or the switch should be disconnected. With my improvements operating the target with the safety mechanism or interlocking mechanism I permit the operator to throw the switch but prevent him from showing a clear signal unless the 35 switch is properly closed for the safety mechanism and target mechanism act in unison and simultaneously. Therefore, the switch must be properly closed in order to indicate a clear signal and the principal object of having the target to act simultaneously 40 and in unison with the interlocking mechanism, as provided by my invention, is to enable any trainman on receiving a signal from the operator that he has properly closed the switch to detect from the position 45 of the signal whether or not the signal given by the operator is correct, while with the present construction of switch stands and targets the operator can operate the switch stand and show a clear signal although the 50 point rail is not in proper closed position and the trainman will be unable to detect by the target whether the switch is properly closed and locked.

Many modifications of my invention may 55 be made without departing from its spirit and scope, and I do not wish to be confined to the exact details shown.

What I claim as new and desire to secure by Letters Patent is:

1. In a device of the character described, 65 a treadle, a housing having a vertical slot therein, pivotally mounted shutters on said housing adapted to permit said treadle to traverse said slot, and means adapted to automatically close said shutters over said slot 70 when the treadle is moved to its uppermost position, substantially as set forth.

2. In a device of the character described, 75 a housing having a vertical slot therein, a foot treadle adapted to traverse said vertical slot, and a pair of shutters adapted to be automatically moved toward each other to normally close said slot and to be operated by the movement of the foot treadle in said slot, substantially as set forth and for 80 the purposes specified.

3. In a device of the character described, 85 a housing having an elongated slot, a treadle mounted to traverse said slot, pivotally mounted shutters and springs adapted to normally hold said shutters in position to close the lower end of said slot and to yield to permit the passage of the treadle therebetween, substantially as set forth.

4. In a device of the character described, 90 a housing having an elongated slot in its end and an inclosure on each side, a foot treadle for said slot, automatic shutters each comprising an elongated vertically disposed member formed integral with an elongated horizontally disposed member, said members being disposed substantially at right angles to each other, said horizontal member having a pivot bearing, and a socket or recess, a pivot on which said horizontal member is pivotally mounted in said inclosure, a spring adapted to engage each socket to hold said shutters in closed position over said slot and permit the shutters to move upon said pivot and to allow said treadle to 100 move in said slot between said shutters and automatically close said shutters when said treadle is in its highest position, substantially as set forth.

5. In a device of the character described, 110 a housing having an elongated vertical slot therein, a foot treadle adapted to move in said slot and having its lower end beveled, a pair of pivotally mounted and spring pressed shutters adapted to normally close 115 said slot and having beveled upper edges adapted to permit the ready passage of said beveled foot treadle between said shutters, substantially as set forth.

FRANK C. ANDERSON.
